(57) **CLAIM**

The ornamental design for a gardening hat with opening, as shown and described.

DESCRIPTION

FIG. 1 is a perspective view showing my new design for a gardening hat with opening;

FIG. 2 is a right view thereof;

FIG. 3 is a left view thereof;

FIG. 4 is a back side view thereof;

FIG. 5 is a front side view thereof;

FIG. 6 is a top view thereof;

FIG. 7 is a bottom view thereof; and,

FIG. 8 is a rear view of the gardening hat in an alternate position.

The broken lines in the drawing figures depict portions of the gardening hat with opening which form no part of the claimed design.

The shade lines on the surfaces of the gardening hat with opening define the contours of the hat and do not reflect a particular surface ornamentation or material.
